UNITED STATES PATENT OFFICE.

GEORGE GODDU, OF WINCHESTER, MASSACHUSETTS, ASSIGNOR TO UNITED SHOE MACHINERY CORPORATION, OF PATERSON, NEW JERSEY, A CORPORATION OF NEW JERSEY.

CONTROLLING MECHANISM.

Application filed March 17, 1919. Serial No. 283,018.

This invention relates to controlling mechanisms and is illustrated herein as embodied in a mechanism for controlling the supplying of metal strips or blanks to an automatic nail making machine.

Letters Patent of the United States, No. 1,396,191, granted Nov. 8, 1921, on my co-pending application, Serial No. 169,562, discloses mechanism for feeding strips to a nail making machine comprising a carrier for presenting the strips to the machine including a nozzle and means controlled by a strip in the carrier for automatically supplying strips to the carrier. One of the objects of the present invention is to provide improved mechanism for controlling the supply of strips to the carrier of the same general character as that forming the subject-matter of said Letters Patent.

To this end, the invention aims to provide means for controlling the operation of the strip supplying means which shall be simpler in construction and more positive and reliable in its operation than the devices hitherto employed for such purpose. In accordance with this feature of the invention, the means carried by the presenting means for initiating the supply of a strip to the presenting means from the supplying means is designed to be rendered inoperative by means operatively connected to the supplying means. Accordingly, operation of the supplying means through a single cycle adapted to supply a single strip to the presenting means prevents further operation of the supplying means until the parts have been reset which is preferably accomplished through the instrumentality of the strip freshly supplied to the presenting means. Preferably, and in the illustrated construction, the controlling means for the supplying means is actuated by a member on the presenting means constructed and arranged for engagement with a strip in the presenting means and comprises a device normally positioned so as to render the supplying means inoperative and a shifter for said device disposed for actuation by the strip engaging member on the presenting means.

Features of the invention relate to a novel clutch mechanism and to a shifter mechanism for connecting and disconnecting the clutch members whereby the driven clutch

member is given one revolution and then automatically disconnected. Another feature of the invention comprises novel mechanism for resetting the shifter mechanism.

Other important features of the illustrated machine are not claimed herein since they are claimed in applicant's patent application, Serial No. 174,078 filed Mar. 9, 1927, which is a division of the present application.

Although the invention will be hereinafter described as embodied in mechanism for feeding strips to a nail making machine, it is recognized that the invention as a whole and certain features thereof are not limited to such use. Accordingly, the scope of the invention is intended to be limited only as required by the claims.

Still other objects of the invention will appear as the description proceeds and will be pointed out in the appended claims.

In the drawings,

Fig. 1 is a view in side elevation of a machine embodying the invention;

Fig. 2 is a view in perspective of the main operating parts of the machine;

Fig. 3 is a plan view of the strip carrier and its supporting frame;

Fig. 4 illustrates the strip carrier and the parts associated therewith for controlling the operation of the strip supplying means;

Fig. 5 is a plan view of the parts shown in Fig. 4;

Fig. 6 is a view in cross-section of the clutch connections between the strip carrier and the strip supplying means showing the controlling means for the strip supplying means;

Fig. 7 is an exploded view of such clutch connections;

Fig. 8 is a detail view showing, in side elevation, the dog which operates the clutch mechanism; and

Fig. 9 is a similar detail view of the levers constituting the shifter mechanism for the dog.

The illustrated machine comprises a frame 2 upon which is mounted a head 4 carrying mechanism for operating on a nail strip which, as shown, includes cutters 6 and 8 moved downwardly by a cam shaft 10 past the edge of a stationary anvil 12. A stop 14 mounted to move with the cutter 6 deter-

mines by its spacing from the edge of the anvil 12 the width of the nail blank severed from the strip.

The nail strip or blank is presented to the cutters 6 and 8 by a tubular carrier 16 the main casting 17 of which is journaled in bearings 18 and 20 of a frame 22 (see Fig. 3) fulcrumed in a yoke-shaped member 24 upstanding from a frame 26. A preferred means for mounting the frame 22 in the yoke 24 comprises studs 28 secured in the yoke by set screws 30 and formed with cone-shaped recesses in their ends adapted to receive the cone-shaped ends of a rod 31 passing through the hub of the frame 22. The frame 22 is slidably adjustable on the rod 31 and may be maintained in any desired position of adjustment thereon by a set screw 32.

The strip carrier 16 is disposed obliquely of the edge of the anvil 12 to the end that the strip may be caused to project further at one of its edges from the anvil than at its other edge so that the blank severed from the strip will taper from one end to the other. It is, of course, necessary to change the relation of the strip to the anvil in order that the blanks severed from the strip subsequently to the first one shall also be tapered. This may be effected in various ways but, in the illustrated construction, the carrier 16 is rotated through an angle of 180° between consecutive operations of the cutters 6 and 8 to present the strip in alternately reversed relations to the cutters by a sprocket chain 33 passing over a sprocket wheel 34 on the carrier 16 and driven from a shaft 36 journaled in the frame 2 of the machine and carrying an eccentric gear 38 meshing with a like gear on a shaft 40 driven by a chain 42 from the cam shaft 10. A link 43 connected to the frame 22 is operated from the shaft 36 to rock the carrier 16 about the fulcrum studs 28 to elevate the carrier and thereby to permit the carrier to be rotated without interference of the strip with the anvil 12. The arrangement of the eccentric gears is such as to rotate the carrier at relatively slow speed when the strip is lowered on the anvil 12 to facilitate the operation of the cutters 6 and 8 on the strip.

The frame 26 may be adjusted laterally of the head 4 so as to vary the degree of taper of the nail blank severed from the strip. As shown, the frame is joined to the head 4 by links 44 and is provided at its rear end with a tongue slidable in a groove 45 in the upper end of a supporting standard 46. The groove 45 is curved substantially concentrically with the point of operation of the cutters 6 and 8 on the strip, and the frame 26 may be adjusted and clamped in said groove in any suitable manner.

The nail strips are fed through the strip carrier 16 by rolls 48 journaled in the cast-

ing 17 and rotated intermittently to feed the strip by pawls 49, which are in turn actuated by a stud 50 with which they are moved into engagement by the rotation of the strip carrier. The stud 50 is carried by an arm 52 (Figs. 2 and 3) pivoted in the frame 22 and coacting with an adjustable stop in the form of a set screw or the like 53 to determine variably the extent of the strip feeding movements of the rolls 48. The pawls 49 are moved in the reverse direction by a spring 54 (Fig. 3) preparatory to a subsequent feeding movement. The arm 52 is maintained in the position determined by the stop 53 by a spring 58 (Fig. 4) coiled about the fulcrum of the arm and extended rearwardly of the frame 22 and adapted to engage one of a series of notches (not shown) on the under surface of the hub of the frame whereby the tension of the spring may be adjusted.

Preferably, and in the illustrated construction, the nail strips are supplied one by one to the strip carrier 16 from a turret 60 comprising a plurality of magazines 62 each constructed to receive a single strip. The magazines 62 are disposed parallel to and concentrically of the axis of the turret which is rotated step by step to align the strips in the magazines successively with the carrier 16 by a Geneva movement designated generally by the numeral 63, Fig. 3, which is operated by a sprocket chain 64 passing over a sprocket wheel 65, the hub of which is mounted loosely on a tubular extension 165 of the strip carrier 16 and is adapted to be clutched thereto when it is desired to supply a strip to the carrier. The sprocket chain 64 drives to a shaft 66 upon which the driving member of the Geneva movement 63 is mounted and which is extended rearwardly of the turret 60 to actuate mechanism for transferring the strips from the magazines 62 to the carrier 16. This transferring mechanism is completely described and claimed in applicant's divisional application referred to above. In order to understand the operation of the controlling mechanism claimed herein it is only necessary to note that when the sprocket wheel 65 is rotated through one revolution, the turret 60 is moved forward far enough to carry one of two adjacent magazines 62 out of and another into alignment with the strip carrier 16 and the transferring mechanism is actuated to transfer the strip in the second magazine to the carrier 16.

Other features of the machine hereinbefore referred to are fully described in the above-mentioned prior Letters Patent, and a more detailed description of such parts of the machine in this application is believed to be unnecessary to a full understanding of the present invention.

In accordance with the invention, the sup-

ply of fresh strips to the carrier 16 is effected automatically so as to maintain a constant supply of strips in the carrier, and the operation of the supplying means is initiated by 5 means on the tubular strip carrier 16 controlled by a strip in the carrier and adapted to actuate controlling means for the clutch connections between the sprocket wheel 65 and the carrier 16. As shown, such connec- 10 tions comprise an enlarged portion 82 on the hub of the sprocket wheel 65 in which is provided a recess 84 to receive a pin 86 having a finger 88 projecting transversely from its middle portion, the pin being flattened 15 at one side of said finger at 90. The flattened portion of the pin 86 is disposed so as to intersect the path in which a lug 92 on the sprocket wheel 34 moves.

The means for controlling the clutch connections between the carrier 16 and the sprocket wheel 65 comprises a dog 94 and a shifter for the dog which, as shown, includes a shaft 96 upon which the dog is loosely mounted and which is journaled in an ex- 25 tension 98 of the bearing 20 of the frame 22. The hub of the dog 94 is maintained normally against a shouldered surface 100 on a wing 102 forming part of the extension 98 by a spring 103 attached at one of its ends to the 30 wing 102 and at its other end to a lug 104 projecting rearwardly from the hub of the dog 94. Mounted on one end of the shaft 96 is an arm 106 having a boss 108 at its lower end in which is seated a plunger 110 urged upwardly by a spring 112. A pin 35 113, see Fig. 6, received in a recess of the plunger 110 limits the upward movement of the plunger. Notches 114 and 116 are formed in the lower surface of the dog 94 to receive the edge of the plunger 110, said 40 notches and spring-pressed plunger providing suitable means for movably connecting the dog 94 and the shifter to each other in either of two relative positions. The shifter 45 further comprises a member 118 on the other end of the shaft 96 formed with divaricate arms 120 and 122 each having its end disposed adjacent to the carrier 16. The dog 94 is formed with an arm 124 underlying 50 the hub of the sprocket wheel 65 and disposed to be engaged by the enlarged portion 82 of said hub simultaneously with the engagement of the arm 106 by a second cam portion 126 on said wheel.

55 The shifter for the dog 94 is actuated by a feeler illustrated as a finger 128 fulcrumed at 130 on the carrier 16 and having one of its ends normally urged towards the path of movement of the strips in the carrier by a spring 131 and its other end 132 projected outwardly from the carrier.

60 The manner of operation of the mechanism by which the supply of fresh strips to the carrier is initiated and controlled will

now be described. Assuming that the finger 128 is in engagement with a strip in the carrier 16, the plunger 110 will be engaged in the notch 116 of the dog 94 which is held against the shoulder 100 of the wing 102 by the spring 103. When the rear end of the strip in the carrier moves past the finger 128, the finger is swung about its pivot 130 by the spring 131 to a position such that upon continued rotation of the carrier the end 132 of the finger impinges upon the end of the arm 120 and through the connection between the plunger 110 and the dog 94 moves the dog from beneath the finger 88. So long as the finger 88 is upheld by the dog 94, the flattened portion of the pin 86 is so disposed relatively to the lug 92 that the lug will pass by said pin during the rotations of the gear 34 without engaging the pin. Upon the withdrawal of the dog 94 from beneath the finger 88, however, the pin 86 upon the force of gravity acting on the finger 88 is turned so as to dispose the flattened end of the pin across the path of movement of the lug 92, so that continued rotation of the gear wheel 34 will cause rotation of the gear wheel 65.

If the gear wheel 65 were to be continuously rotated, a number of strips would be forced into the strip carrier which is designed to receive but one strip at a time. The introduction of more than a single strip into the carrier upon the initiation of the operation of the strip supplying means is, in the operation of the illustrated construction, prevented by movement of the arm 106 outwardly by the cam 126 while the dog 94 is withheld from movement by the action of the enlarged portion 82 of the wheel on the arm 124 of the dog. Such movement of the arm 106 carries the arm 120 away from the carrier 16 and out of the path of movement of the end 132 of the finger 128, the plunger 110 being at the same time moved from the notch 116 to the notch 114. While the plunger 110 engages notch 114 the dog 94 is held in such relation to the arm 106, and to the arm 120 which is rigidly connected thereto through shaft 96, that when cam portion 126 passes away from arm 106 arm 120 is held out of the path of movement of the end 132 of finger 128, and this in spite of the fact that dog 94 is held by spring 103 in the path of movement of finger 88. Thus looking at the parts from the direction in which they are viewed in Fig. 6, and assuming them to be with dog 94 held by spring 103 in the position there shown, when the plunger 110 is moved from the position there shown to the position in which it engages notch 114, arms 106 and 120 move counter clockwise to such an extent that the extremity of arm 120 is no longer in the path of movement of the end 132 of finger 128. It will be understood

that the dog 94 is returned into the path of movement of the finger 88 by the spring 103 immediately after the finger 128 passes out of contact with the end of the arm 120. Accordingly, when the gear wheel 65 has completed a single revolution, the finger 88 on the pin 86 will be again engaged by dog 94, inasmuch as the arm 120 is no longer in position to be actuated by the finger 128, and will turn the pin to unclutch the gear wheel 65 from the gear wheel 34. With this construction, only a single operation of the supplying means designed to supply a single strip to the carrier is effected whether a strip is actually supplied to the carrier or not.

When a fresh strip is introduced into the carrier, it pushes back the inner end of the finger 128, thereby positioning the end 132 of the finger so as to wipe upon the upper surface of the arm 122. Since the dog 94 abuts against the shoulder 100 of the wing 102 and is thus precluded from movement with the shifter, the wiping of the end 132 of the finger 128 on the arm 122 moves the shifter relatively to the dog so as to carry the plunger 110 from the notch 114 back into the notch 116 thus resetting the clutch controlling means. This completes the cycle of operations, the end 132 of the finger 128 being then maintained out of operative relation to the arm 120 against the tension of the spring 131 by the strip until the rear end of the strip passes from engagement with the finger 128 after which the finger will again actuate the arm 120 to initiate the supply of another strip to the carrier.

Having fully described my invention, what I claim as new and desire to secure by Letters Patent of the United States is:—

1. Power-transmission mechanism comprising disconnectible driving and driven clutch members tending normally to remain in clutching relation, means normally effective to unclutch said members, and means operated by the driving member of said clutch members to render said unclutching means ineffective to maintain unclutched relation of said clutch members and thereafter operated by the driving member to render said unclutching means effective not later than at the conclusion of a single revolution of said driven clutch member.

2. Power transmission mechanism comprising, a driving member, a driven member, means for controlling the operation of the driven member, means carried by the driving member for actuating the controlling means, and means movable by the driven member for altering the relation between the driving member and on the controlling means from a cooperative relation to a non-cooperative relation.

3. Power transmission mechanism comprising, a driving member, a driven member,

controlling means for the driven member tending normally to disconnect the driven member from the driving member and constructed and arranged when actuated adversely to said tendency to permit a single cycle of operations of the driven member, means carried by the driving member for so actuating the controlling means, and means movable by the driven member for preventing recurrence of such actuation of the controlling means by the driving member.

4. Power transmission mechanism comprising, a driving member, a driven member, means for controlling the operation of the driven member, means carried by the driving member for actuating the controlling means, and means movable with the driven member for moving the controlling means out of operative relation to the driving member.

5. Power transmission mechanism comprising, a driving member, a driven member, means for controlling the operation of the driven member comprising a device normally operative to disconnect the driven member from the driving member, means carried by the driving member for moving said device out of operative position, and means movable with the driven member for rendering the driving member inoperative on said device.

6. Power transmission mechanism comprising, a driving member, a driven member, a device normally operative to disconnect the driven member from the driving member, means carried by the driving member for moving said device from operative position to cause the driven member to be connected with the driving member, means for effecting reverse movement of said device again to disconnect the driven member from the driving member, and means movable with the driven member for rendering the driving member inoperative on said device.

7. Power transmission mechanism comprising, a driving member, a driven member, a device operative normally to disconnect the driven member from the driving member, means carried by the driving member for moving said device to cause the driven member to be connected with the driving member, yielding means for effecting reverse movement of said device again to disconnect the driven member from the driving member, mechanism movable with the driven member for rendering the driving member inoperative on said device, and means for retaining said device against movement during the operation of said mechanism.

8. Power transmission mechanism comprising, a driving member, a driven member, a device for controlling the operation of the driven member, yielding means for maintain-

ing said device normally operative to disconnect the driven member from the driving member, a shifter connected with said device and movable relatively thereto toward and

5 from the driving member means on the driving member for actuating the shifter to move said device out of operative position, means movable with the driven member for moving said shifter out of operative relation
10 to the actuating means, and means movable with the driven member for retaining said device against movement during movement of the shifter.

9. Power transmission mechanism comprising, a driving member, a driven member, a device for controlling the operation of the driven member, yielding means for maintaining said device normally operative to disconnect the driven member from the driving member, mechanism for transmitting motion to said device movable relatively to said device, means movable with the driven member for moving said mechanism relatively to said device, and means for retaining the device against movement during operation of said moving means.

10. Power transmission mechanism comprising, a driving member, a driven member, a device for controlling the operation of the driven member, yielding means for maintaining said device normally operative to disconnect the driven member from the driving member, a shifter movably connected to said device and comprising a part disposed adjacent to the driving member, means carried by said driving member and operable on said part when the shifter is in one position relatively to said device to move said device out of operative position to cause the driven member to be connected with the driving member, means operable on a second part of said shifter for moving said first-mentioned part out of operative relation to the driving member and a third part carried by said shifter and operable by the driving member to move said first-mentioned part back into operative relation with the driving member.

11. Power transmission mechanism comprising, a driving member, a driven member, a device for controlling the operation of the driven member, yielding means for maintaining said device normally operative to disconnect the driven member from the driving member, a shifter movably connected to said

55 device comprising a part disposed adjacent to the driving member, an actuating member movably mounted on the driving member and operable on said part when in one position to move said device out of operative position to cause the driven member to be connected with the driving member, means operable on a second part of said shifter for moving said first-mentioned part out of operative relation to the actuating member, and
60 a third part carried by said shifter and

operable by the actuating member when in another position to move said first-mentioned part back into operative relation to the driving member.

12. Power transmission mechanism comprising, a driving member, a driven member, a device for controlling the operation of the driven member, yielding means for maintaining said device normally operative to disconnect the driven member from the driving member, a shifter for said device movable relatively to the device, connections between the shifter and said device constructed to retain the shifter yieldingly in either of two positions relatively to said device, means carried by the driving member and operable on a part of said shifter to move the device out of operative position, means operable on a second part of said shifter to move said shifter from one position to another relatively to said device to carry the first mentioned part out of operative relation to the driving member, and a third part on said shifter and operable by the driving member to effect reverse movement of the shifter and said device to redipose said first-mentioned part in operative relation to the driving member.

13. Power transmission mechanism comprising, a driving member, a driven member, a device for controlling the operation of the driven member, yielding means for maintaining said device normally operative to disconnect the driven member from the driving member, a shifter for said device movable relatively to the device, connections between the shifter and said device constructed to retain the shifter yieldingly in either of two positions relatively to said device, means carried by the driving member and operable on a part of said shifter to move the device out of operative position, means operable on a second part of said shifter to move said shifter from one position to another relatively to said device to carry the first-mentioned part out of operative relation to the driving member, means for retaining the device against movement during movement of the shifter, and a third part carried by said shifter and operable by the driving member to effect reverse movement of the shifter and said device to redipose said first-mentioned part in operative relation to the driving member.

14. Power transmission mechanism comprising, a driving member, a driven member, clutch mechanism for connecting said members, a clutch controlling device operative normally to disconnect the driven member from the driving member, said clutch mechanism and clutch controlling device being constructed and arranged to cause movement of the driven member through a single cycle of operations when the clutch controlling device is actuated, means carried by the

driving member for actuating the clutch controlling device, and means movable with the driven member for rendering the driving member inoperative on the clutch controlling device.

15. Power transmission mechanism comprising, a driving member, a driven member, clutch mechanism for connecting the driving member and the driven member, a clutch controlling device operative normally to disconnect the driven member from the driving member, a shifter for the clutch controlling device movable relatively to said device, means carried by the driving member for moving the clutch controlling device out of operative position to cause operation of the driven member, and means movable with the driven member for effecting relative movement of the shifter and said device to render the driving member inoperative on the shifter.
- 10 16. Power transmission mechanism comprising, a driving member, a driven member, clutch mechanism for connecting the driving member and the driven member, a clutch controlling device operative normally to disconnect the driven member from the driving member, a shifter for the clutch controlling device movable relatively to the clutch controlling device, means carried by the driving member for moving the clutch controlling device out of operative position to cause operation of the driven member, and cam mechanism movable with the driven member for effecting movement of the shifter relatively to the clutch controlling device to carry the shifter out of operative relation to the driving member.
- 20 17. Power transmission mechanism comprising, a driving member, a driven member, clutch mechanism for connecting the driving member and the driven member, a clutch controlling device operative normally to disconnect the driven member from the driving member, a shifter for the clutch controlling device movable relatively to the clutch controlling device, means carried by the driving member and operable on the shifter to move the clutch controlling device out of operative position to cause operation of the driven member, means movable with the driven member for rendering the driving member inoperative on said device and means carried by the shifter and operable by the driving member for rendering the driving member again operative on said device.
- 25 18. Mechanism for controlling the supply of blanks to a machine comprising a shifter having a pair of arms and a feeler arranged to occupy either one of two positions dependent upon the presence or absence of a blank, and operable in one of said two positions to engage one of the arms of the

shifter and in the other position to engage the other arm of the shifter.

19. Mechanism for controlling the supply of blanks to a machine comprising rotary driving and driven members, a feeler rotating with the driving member and occupying either one of two positions dependent upon the presence or absence of a blank, a clutch having co-operating parts operatively connected to the driving and driven members respectively, a shifter having a pair of arms, one of which extends into the path of movement of the feeler in the presence of a blank, and the other of which extends into the path of movement of the feeler in the absence of a blank, and connections from the shifter to the clutch arranged to render the clutch operative to transmit power from the driving to the driven member to cause a single cycle of operation of the driven member when a blank passes out of engagement with the feeler.

20. Mechanism for controlling the supply of blanks to a machine comprising rotary driving and driven members, a feeler arranged to be engaged and positioned by a blank and having two positions dependent upon the presence or absence of a blank, a clutch having co-operating members operatively connected to the driving and driven members respectively, clutch-controlling means by or through which said feeler renders the clutch effective to operate in consequence of the passing of a blank out of contact with said feeler, and means for causing said controlling means to render the clutch inoperative at the conclusion of a single cycle of operation.

21. Mechanism for controlling the supply of blanks to the machine comprising rotary driving and driven members, means for controlling the operation of the driven member comprising a controlling member normally positioned to render the driven member inoperative, a shifter movably connected to said controlling member, means rotating with the driving member and operable on said shifter to move said controlling member from its normal position to cause transmission of power to the driven member, and means movable with the driven member for effective relative movement of said shifter and said controlling member to interrupt the transmission of power to the driven member.

22. Mechanism for controlling the operation of machine parts comprising a member positioned normally to render said machine parts inoperative, a shifter connected to said member and movable relatively thereto, a finger carried by a rotating part of the machine and operable on said shifter to move said member to a position to render said machine parts operative, and cam mechanism operatively connected to said machine parts.

for moving said shifter out of operative relation to said machine parts.

23. Mechanism for controlling the supply of blanks to a machine comprising driving and driven members, a disconnectible self-coupling clutch including means arranged to control the coupling and effect uncoupling of the driving and driven members, a feeler arranged to contact with a blank and to 10 actuate the controlling means according to whether it is or is not engaged by a blank, and means movable with the driven member to cause the controlling means operatively to disconnect the driving and driven members when the driven member has moved 15 through a single cycle of operation.

In testimony whereof I have signed my name to this specification.

GEORGE GODDU.
